(57) **CLAIM**

We Claim the ornamental design for an electrical connection mechanism, as shown and described.

DESCRIPTION

FIG. 1 is an upper right frontal perspective view of the electrical connection mechanism comprising the present invention;

FIG. 2 is a top plan view thereof;

FIG. 3 is a left side elevational view, with the right side being a mirror image thereof;

FIG. 4 is a bottom plan view thereof;

FIG. 5 is a front elevational view thereof; and,

FIG. 6 is a rear elevational view thereof.
